SPEED ADJUSTMENT DEVICE
Frank W. Broderick, P.O. Box 2, Stirling, N.J.
Filed Dec. 4, 1963, Ser. No. 328,081
2 Claims. (Cl. 74—665)

This invention relates to selectively increasing or decreasing the speed of rotation momentarily of a constant rotational speed device while running.

In the operation of a rotary printing press having a mated set of embossing rolls to effect an exact register of printing with embossing and wherein said printing rolls and said embossing rolls are driven from a common constant speed shaft, it occasionally happens that the printing and the embossing become out of register often by a small distance.

Such out-of-register between printing and embossing in the length of the web being printed is very noticeable and hence undesirable.

Up to now it was practically impossible to bring these out of register effects into register while the machine is running at high speed.

By the use of the invention herein the out of register embossing may be brought into register while the machine is running at constant speed.

It is an object of this invention to provide means for selectively increasing or decreasing momentarily the speed of a constantly rotating axle.

It is another object to provide a speed adjustment device on the embossing mechanism of a constant speed printer-embosser whereby out of register embossing may be brought into register with the printing while the machine is running at a constant high speed.

These and other advantages of this invention will become apparent upon reading the following descriptive disclosure of several illustrative embodiments thereof shown in the accompanying drawing and in which:

FIG. 1 is a top plan view of the device, broken away in part to show the details thereof and electrical actuation means.

FIG. 2 is a section view taken on line 2—2 of FIG. 1.

FIG. 3 is a partial view showing the use of hydraulic actuation means in lieu of the electrical actuation means of FIG. 1, and

FIG. 4 is a block diagram of the electric eye modification of this invention.

Turning to the drawing, a constant speed drive shaft 10 used to operate all printing rolls and the embossing rolls is secured to a constant speed motor (not shown).

The shaft 11 to power the embossing rolls is provided with a suitable helical gear 12 conventionally fixedly secured thereto.

The common drive shaft 10 is provided with a bevel gear 13 and a co-acting bevel gear 14 is fixedly secured to a rotatable shaft 15.

In conventional practice shaft 15 is provided a conventional gear which drives another conventional gear on shaft 11 of the embossing roll.

However, according to this invention shaft 11 is provided with a relatively narrow helical gear and shaft 15 is provided with a relatively wide helical gear 16.

The gear 12 is fixed to shaft 11 but gear 16 is slideable on shaft 15 while it is rotating at constant speed.

To bring about this sliding effect of gear 16 on shaft 15 while shaft 15 is rotating at constant speed, the shaft 15 is provided with a suitably long slot 17 located adjacent gear 12. Also the gear 15 on its inner cylindrical surface is provided with a co-acting slot 17X. A key 18 is disposed in slots 17 and 17X locking the gear 16 to shaft 15 to prevent rotational movement of one relative to the other. Yet wide gear 16 is linearly slideable in

2

shaft 15 due to the linear key 18 disposed in slots 17 and 17X.

In order to move the rotating wide gear 16 a bifurcated yoke 20 is provided, the forks 21 and 21X of which engage the respective ends of the gear 16.

The forks 21 and 21X preferably are in sliding engagement with the rotating flat end walls 22 of the gear 16. To this end, the forks are each preferably provided short stout abutments 23 of small area which may be curved in part around shaft 15.

Various controlled means may be used to move the yoke 20 a small distance as desired. FIG. 1 shows the use of an electric motor 30 actuating a threaded shaft 31 of suitable small spiral grooves.

As shown in FIG. 1 the yoke 20 is provided with a pair of holder bifurcations 24 of suitable thickness, each of which are provided with screw threaded apertures to receive threaded shaft 31.

Clearly rotation of shaft 31 moves the yoke 20 along the shaft 15 and hence the wide helical gear 16.

The yoke 20 may be moved linearly by hydraulic means (FIG. 3).

In this case the bifurcations 24 are secured to a piston rod 40 by means of set screws 41. The piston rod is moved by hydraulic piston 42 by manipulation of the controls 43.

Where electric, hydraulic and like means are used to control the movement of yoke 20, their actuation may be effected by electric eyes, which eyes are actuated by sensing means sensing out of register conditions.

The actuation of yoke 20 hence may be variously effected manually, mechanically and otherwise.

The device of this invention is useable with the invention set forth in Broderick U.S. 3,088,399 by connecting gear 12 to the shaft 22Y of said patent.

This invention is clearly of a generic scope and not limited to the illustrations of this disclosure.

I claim:

1. A speed adjustment device for selectively momentarily adjusting the speed of one of a pair of constantly engaged shafts each normally running at constant speed comprising a relatively narrow helical gear fixedly secured to the driven shaft, the speed of which is to be adjusted; a relatively wide helical gear having a keyway slot in its aperture; a driver shaft having a longitudinal channel therein; a key disposed in said driver shaft channel and in said wide helical gear slot permitting longitudinal movement of said wide gear on said keyway; and bifurcated means for selectively sliding said wide helical gear having respective forks of which slidably engage the respective opposing end walls of said wide gear and actuating means actuated by an electric eye for moving said bifurcated means parallel to the axis of the driver shaft, whereby the speed of said driving gear is adjusted by frictional sliding on the incline plane surfaces of said wide helical gear.

2. The device of claim 1 wherein said actuating means for moving said bifurcated means is a hydraulic piston.
